UNITED STATES PATENT OFFICE.

HERBERT H. HEWITT, OF BUFFALO, NEW YORK.

CAR-AXLE JOURNAL-BOX.

1,098,500.

Specification of Letters Patent. Patented June 2, 1914.

Application filed September 5, 1911. Serial No. 647,561.

To all whom it may concern:

Be it known that I, HERBERT H. HEWITT, a citizen of the United States, and a resident of Buffalo, county of Erie, and State of New York, have invented certain new and useful Improvements in Car-Axle Journal-Boxes, of which the following is a full, clear, and exact description.

The present invention relates to car axle journal boxes and seeks to provide an improved arrangement of journal box and roller bearings for the car axle by which the free rocking movement of the car axle is permitted and by which the bearing rollers are held against displacement and accurately in line with the cylindrical surfaces between which they are interposed.

In accordance with the preferred plan, the journal box comprises a spherical body portion having a transverse, cylindrical chamber therein for receiving the projecting end journal of the car axle. A sleeve is loosely fitted upon the journal and within the cylindrical chamber of the box and the bearing rollers are interposed between the sleeve and the journal box, the sleeve and box being preferably provided with shoulders engaging the ends of the rollers and preventing the displacement thereof.

The journal box is mounted in a vertically movable support carried by or forming a portion of the car truck and the support is provided with a concave spherical seat in which the journal box is mounted to shift universally. By this arrangement, the car axle is free to rock in a transverse plane as the car passes over irregularities of the track and the sleeve and rollers are properly maintained in position and relieved of the ill effects of the great shocks and strains to which they are subjected. Furthermore, by reason of this arrangement, the sleeve acts as a supplemental or emergency bearing for the car axle journal in case the bearing rollers are rendered inoperative. While this sleeve forms an important element of the invention, it may be omitted and the rollers arranged to directly engage the car axle journal without departure from the broad scope of the invention.

The invention will be more fully understood upon reference to the following detail description, taken in connection with the accompanying drawings, which illustrate

the preferred embodiments thereof. The scope of the invention is particularly pointed out in the appended claims.

In the drawings, Figure 1 is a plan view of a portion of the car truck with the present improved journal box applied thereto. In this figure the portion of the truck supporting one of the journal boxes is shown in section. Fig. 2 is a view in elevation of the parts shown in Fig. 1. Fig. 3 is a vertical section on the lines 3—3 of Figs. 2 and 4. Fig. 4 is a cross-section on the lines 4—4 of Figs. 2 and 3. Figs. 5 and 6 are views similar to Fig. 3, illustrating other embodiments of the invention. Fig. 7 is a section on the lines 7—7 of Figs. 5 and 6.

The wheel axles 10 are provided with wheels 11 fixed thereto and with projecting journals 12 at their ends. These journals, contrary to the usual practice, are preferably cylindrical throughout and are not provided with the usual collars and shoulders at their outer and inner ends. The journal box 13 comprises an annular, spherical body portion and is provided with a transverse, axially cylindrical chamber 14 within which the projecting end journal of the car axle extends. A one-piece cylindrical sleeve 15 fits loosely within the chamber 14 and is loosely and removably mounted upon the axle journal 12. At its outer end, the sleeve 15 abuts against an internal shoulder 16 formed upon the journal box at the outer end of the cylindrical chamber thereof. The internal bore of the sleeve is preferably slightly larger than the journal 12 and the internal diameter of the sleeve is preferably slightly smaller than the diameter of the cylindrical chamber 14 of the journal box.

The journal box is provided with a projecting rear end portion 17 having an annular, plane, rear end face which, when the sleeve 15 is in position, coincides with the plane, annular, rear end face of the sleeve. An annular, axially resilient guard 18 is mounted upon the journal between the journal box and wheel and preferably comprises a coiled spring formed of a strip of flat steel and the inner and outer rings of which respectively engage the hub 19 of the wheel 11 and the coincident inner end faces of the sleeve 15 and of the rearwardly projecting end portion 17 of the journal box. The guard thus serves to hold the bearing sleeve

15 in position, as well as to exclude dirt and prevent the escape of lubricant from the box.

A series of bearing rollers 20 are interposed between the sleeve and the journal box, said rollers being somewhat shorter than the sleeve 15 and the chamber of the box. The wall of the chamber and the exterior surface of the sleeve are provided with annular recesses forming a raceway for the rollers and also forming shoulders 21 and 22 extending over the ends of the rollers and holding the same against longitudinal displacement. The bearing rollers are preferably spaced by a series of rollers 23 of slightly smaller diameter, the bearing rollers 20 and spacing rollers 23 being alternately arranged within the grooves or raceways of the sleeve and the journal box, thus dispensing with the use of spacing cages and the like, which would readily get out of order and interfere with the proper operation of the bearing under the great shocks and strains to which the parts of a car truck are subjected.

To assemble the parts, the spherical body of the journal box is formed of separate sections that are preferably divided upon a vertical central plane, transverse to the axis of the journal. These annular, semi-spherical sections are connected by means of a series of screw bolts 24 or, if desired, long heavy rivets could be employed.

The outer section of the journal box is provided with a projecting hollow part 25 which forms a chamber for receiving lubricant. An axial opening in this projecting portion and through which lubricant is supplied, is normally closed by a screw plug 26. Thick grease is preferably employed and is supplied from the lubricant chamber within the projecting portion 25 to the bearing surfaces of the sleeve 15, chamber 14 and rollers 20.

The spherical journal box is mounted within the correspondingly shaped concave seat on a suitable vertically movable support mounted on the truck frame, so that the wheel axle is free to rock in a transverse vertical plane and so that the journal box is free to shift universally with the axle and thereby prevent this rocking movement from straining and displacing the parts of the bearing. The supporting or retaining members for the journal box may be applied to different forms of trucks and mounted thereon in different ways. In the drawings, the improved journal box and bearing is shown as applied to a freight car truck comprising side frames (only one of which is shown in the drawing) which are swiveled upon the ends of the transverse connecting transom. As shown, the side frame 27 is provided at its ends with openings for receiving the spherical journal boxes and the supporting members or keepers for the

journal box comprise rings 28 which are threaded within the openings. The inner surfaces of these supporting or retaining members or rings are shaped to correspond to and fit upon the spherical journal box and thereby form the annular, spherical, concave seat in which the journal box is free to shift universally with the axle as the latter rocks in passing over irregularities of the track. The rings or keepers are preferably provided with flanges 28' which abut against the inner and outer faces of the side frame 27 and set screws 29 threaded through the ends of the side frames engage notches formed in the inner adjacent edges of the ring keepers to hold the latter in position. These set screws are provided with lock nuts 30.

The transom 31 of the car truck is provided with a cylindrical end portion 32 which is journaled within a central flanged opening in the side frame 27. Keepers 33 are arranged within sockets in the walls of the flanged opening of the side frame and are secured in position by pins 34. These keepers extend through slots in the cylindrical portion 32 of the transom to hold the side frame thereon, but, in such a manner, that the side frame is free to swing upon the end of the transom to permit the vertical movement of the ends of the side frames and of the wheels and wheel axles connected thereto in passing over irregularities of the track. The manner of mounting the spherical journal boxes also permits the free rocking movement of the wheel axles and at the same time maintains the sleeves 15 and the rollers 20 in proper position and in alignment with the journals, so that these parts are well adapted to withstand the shocks and strains to which they are subjected. Moreover, inasmuch as the journals can rotate within the sleeve 15, these sleeves act as supplemental or emergency bearings for the journals in case the rollers fail.

In the form shown in Figs. 5, 6 and 7, the bearing sleeve is dispensed with and it is unnecessary to form the spherical journal box 13' of separate sections. In each of these constructions the bearing and spacing rollers 20 and 23 are interposed directly between the cylindrical surfaces of the journal and the chamber of the spherical journal box. In the form shown in Fig. 5, the outer ends of the rollers abut against a shoulder 36, while the inner ends thereof are coincident with the inner end face of the journal box and are engaged and held in position by the annular resilient guard 18. In the form shown in Fig. 6, the ends of the rollers abut against internal shoulders 36 and 37 formed at the opposite ends of the journal box. In other respects the constructions are similar to each other and to the form shown in Figs. 3 and 4.

It is obvious that the improved journal box and roller bearing can be mounted upon trucks differing widely in construction from that illustrated and that other changes may be made in the details set forth without departure from the essentials of the invention as defined in the claims.

I claim as my invention:

1. The combination with a car axle having a wheel thereon and a projecting journal at its end, of a box having a cylindrical chamber therein for receiving said journal, a sleeve loosely mounted on said journal and loosely fitting in the cylindrical chamber of said box, a series of bearing rollers interposed between said sleeve and said box, and a support whereon said box is movably mounted to permit the free rocking movement of said axle and maintain said sleeve and rollers in line with said journal.
2. The combination with a car axle having a wheel thereon and a projecting journal at its end, of a box having a cylindrical chamber therein for receiving said journal, a sleeve loosely mounted on said journal and loosely fitting in the cylindrical chamber of said box, a series of bearing rollers interposed between said sleeve and said box, and a vertically movable support wherein said journal box is universally movable to permit the free rocking movement of said axle and maintain said sleeve and rollers in line with said journal.
3. The combination with a car axle having a wheel thereon and a projecting journal at its end, of a journal box comprising a spherical body portion having a cylindrical chamber therein for receiving said projecting journal, a sleeve loosely mounted on said journal and loosely fitting in the cylindrical chamber of said box, a series of bearing rollers interposed between said sleeve and said box, and supporting members or keepers having a spherical concave seat wherein said box is universally shiftable.
4. The combination with a car axle having a wheel thereon and a projecting journal at its end, of a journal box comprising a spherical body portion having a cylindrical chamber therein for receiving said projecting journal, a sleeve loosely mounted on said journal and loosely fitting within the cylindrical chamber of said box, a series of bearing rollers held against longitudinal movement and interposed between said sleeve and the wall of the cylindrical chamber of said box, and a support having a spherical concave seat wherein said journal box is movably mounted.
5. The combination with a car axle having a wheel thereon and a projecting journal at its end, of a journal box comprising a spherical body portion having a cylindrical chamber therein for receiving said projecting
- journal, a sleeve loosely mounted on said journal, a series of bearing rollers interposed between said sleeve and the wall of said cylindrical chamber, a series of relatively small spacing rollers between said bearing rollers, and a support having a spherical concave seat wherein said box is movably mounted.
6. The combination with a car axle having a wheel thereon and a projecting journal at its end, of a journal box comprising a spherical body portion having a cylindrical chamber therein for receiving said projecting journal, a sleeve loosely mounted on said journal, a series of alternately arranged bearing and spacing rollers held against longitudinal movement and interposed between said sleeve and said box, and connected, vertically movable, supporting members or keepers having a spherical concave seat wherein said box is universally movable.
7. The combination with a car axle having a wheel thereon and a projecting journal at its end, of a journal box comprising a spherical body portion having a cylindrical chamber therein for receiving said projecting journal, a sleeve on said journal, a series of bearing rollers interposed between said sleeve and said box, said sleeve and box having shoulders engaging the ends of said rollers and said box comprising separate sections secured together, and connected supporting members or keepers having a spherical concave seat wherein said box is removably mounted and free to shift universally.
8. The combination with a car axle having a wheel thereon and a projecting journal, of a journal box having a cylindrical chamber therein, a sleeve loosely mounted on said journal and loosely fitted within said chamber, a series of bearing rollers interposed between said sleeve and the wall of said chamber, said sleeve and the wall of said chamber being recessed to receive said rollers, and a support whereon said box is movably shiftable.
9. The combination with a car axle having a wheel thereon and a projecting end journal, of a journal box comprising a spherical body portion having a transverse cylindrical chamber therein for receiving said projecting journal, a sleeve loosely and rotatably fitted upon said journal and within said chamber, a series of bearing rollers interposed between said sleeve and box, and supporting members having a spherical concave seat for said box, said journal box having a projecting hollow part closing the outer end of said chamber and adapted to receive lubricant and supply the same to said rollers and said sleeve.
10. The combination with a car axle having a wheel thereon and a projecting journal at its end, of a journal box comprising a spherical body portion having a cylindrical chamber therein for receiving said project-

ing journal, a series of cylindrical bearing rollers arranged in said chamber and interposed between said journal and said box, and a member pivotally mounted to swing in
5 vertical direction and having a support provided with a spherical concave seat wherein said journal box is universally shiftable to

permit the free rocking movement of said axle and maintain said rollers in line with said journal, substantially as described.
